UNITED STATES PATENT OFFICE.

JULIUS HARWOOD MASON AND HALLOCK BERNARD MASON, OF DUNCAN FALLS, OHIO.

BOTTLE-RECEPTACLE.

1,106,050.

Specification of Letters Patent.

Patented Aug. 4, 1914.

Application filed September 27, 1912. Serial No. 722,651.

To all whom it may concern:

Be it known that we, JULIUS HARWOOD MASON and HALLOCK BERNARD MASON, citizens of the United States, residing at Duncan Falls, in the county of Muskingum and State of Ohio, have invented new and useful Improvements in Bottle - Receptacles, of which the following is a specification.

Our invention relates to receptacles for the deposit of milk bottles or other articles, to hold the same against theft or tampering therewith by unauthorized persons or by animals.

One object of the invention is to provide in such a device a plurality of yielding members between and by which a bottle or the like is supported, in connection with means to lock the members after insertion of the bottle so that the same cannot be removed by anyone other than the owner or other person possessing a key to the lock.

Another object of the invention is to provide means operable upon the insertion of the bottle or the like to move a ticket, coupon or coin to a position where it can be readily connected by the milkman.

Another object of the invention is to provide means for simultaneously operating the yielding bottle supporting members and the ticket presenting means.

A further object of the invention is to generally improve the construction of a device of this kind.

Minor objects will appear from the description following taken in connection with the accompanying drawings, wherein:—

Figure 1 is a front elevation. Fig. 2 is a vertical sectional view looking toward the front of the device. Fig. 3 is a transverse sectional view on the line $a-a$ of Fig. 2, and, Fig. 4 is a plan view of the ticket or coin holder employed.

In the drawings, like reference characters designate like parts throughout the several views.

Referring specifically to the drawings, a hollow receptacle is provided which is open at its bottom and which comprises a front wall 1, a rear wall 2, side walls 3 and a cover 4 or top 4. This receptacle may be constructed of any suitable material, for instance wooden boards, which boards are rigidly fastened together in any suitable manner, as by means of nails or screws as at 5.

Interior of the receptacle and transversely

of each side wall 3, is secured a bar 6 forming ledges. Upon each ledge rests a bottle supporting plate 7, which plates 7 are hinged to the sides as at 8. Said plates 7 are normally and yieldingly maintained against the ledges 6 by means of coil springs 9, which have arms bearing against the plates and against the sides 3. The plates 7 as shown best in Figs. 2 and 3, are cut away to provide a semi-circular edge 10 at their center, which cut away portions of the plates 7 form an annular opening. Around the edges 10 at the lower part thereof, the plates 7 are cut away or grooved concavely to conform to the shape of the bead at the mouth of a milk bottle.

To the interior face of the front 1 are secured guide strips 12, between which is adapted to slide a plate operating member 13. Said member 13 is pointed or provided with beveled edges 14 leading to a point at the top so that the same will be wedge-shaped. The point of this wedge portion extends between the plates 7 to one side of the semi-circular opening provided between the same.

To the wedge operating member is connected a pin 15 which extends through a vertical elongated slot 16 in the front 1, and beyond which front on the exterior thereof, the pin 15 is provided with an operating knob 17. To said knob 17 is hinged a leaf or hasp 18 provided with an opening through which is adapted to project a staple 19 provided on a suitable plate secured to the front 1. A padlock 20 or its equivalent, is adapted to engage the staple 19.

A spring device comprising cross arms 21 at the junction of which is provided a coil 22, is secured as at 23 to the rear wall 2. The coil 22 is arranged directly above so as to be in the path of movement of the plate 13, whose point at the wedged portion thereof engages the coil. Supported from said spring device and preferably centrally of the opening between the plates 7, is a plunger pin 24 movable in a slot in a plate 25, secured to the receptacle below the cover 4. Above the plate 25 the plunger 24 is provided with an enlarged head 26 to limit its movement interiorly of the receptacle. Said enlarged head 26 moves in a suitable slot provided in the cover 4.

Upon the cover 4 and surrounding the plunger, is secured a frame 27 by means of

tangs and suitable fastening devices as at 28. Interior of said frame and filling the space thereof as much as possible, is a plate 29 hinged at 30. Said plate 29 is preferably 5 provided with a transparent panel 31.

At a suitable location exterior of the box, is provided a fork-shaped or bifurcated member 32 fastened to the receptacle at 33. Empty bottles may be supported from the 10 member 32.

As is obvious, the device is particularly adapted to be secured exterior of a building, as against a wall or to a post, and to this end suitable means is provided to facilitate fastening to such a structure. The 15 specific means shown consists of tangs 34 having openings 35 through which suitable fastening means to engage the support and suspend the receptacle, is passed.

20 In operation, when inserting a milk bottle into the receptacle, the hasp 18 is disengaged from the staple 19. Thereupon the knob 17 is pulled upwardly to raise the wedge plate 13 to its limit. During such movement the 25 inclined edges 14 act against the plates 7 and raise the same, and accordingly present a larger opening between the same. Simultaneously with the opening of the plates 7 the wedge member 13, by the engagement of 30 its point with the coil 23, raises the plunger 24 which in turn raises the plate or leaf 29. Preparatory to the placing of the milk bottle in the receptacle, the owner of the box inserts or places a coupon, ticket or 35 coin interior of the frame 27 and upon the plunger 24, so that upon the operation of the plunger 24, the ticket or the like and the plate 29 will be raised. In such raised position the milkman can easily collect the ticket 40 or coin. The plate 29 by reason of its close relation with the walls of the frame 27, renders it exceedingly difficult for said plate 29 to be raised for the purpose of removing the ticket or coin unless operated by the 45 slide or wedge plate 13. By means of the provision of the transparent panel 31, the driver or owner can see at a glance whether or not the necessary ticket or coin is within the frame 27. After the plates 7 have been 50 raised as described, the milk bottle is inserted through the opening at the bottom of the receptacle, and after the removal of the ticket or coin the knob 17 is released, whereupon the springs 9 and the spring member 55 of the plunger will restore the parts to normal position as in Fig. 2, in which position the milk bottle will be supported, its ledge or bead at the mouth thereof resting upon the plates 7 and around the edges 10. Upon 60 the return of the knob 17 and accordingly the slide or wedge plate to normal position, the hasp 18 is moved over the staple 19, whereupon the lock 20 is secured or applied to the staple by the milkman.

65 It is to be understood that the device is

not limited to use in connection with milk bottles, as it is obvious that the same may be used in connection with various articles.

As we have only illustrated the preferred form of the device, it is to be understood that changes in the details of construction thereof may be made without departing from the spirit and scope of the invention as set forth in the appended claims.

Having thus described our said invention, 75 what we claim and desire to secure by Letters Patent is:—

1. In a device of the class described, a receptacle having its cover fastened to prevent removal of an article thereat, article supporting means within the receptacle, and a shifting member to actuate said means for the reception or removal of an article through downward movement.

2. In a device of the class described, a receptacle, article supporting means including an article supporting plate in said receptacle, a rest for said plate, a spring to maintain said plate against said rest, a shifting member movable against said plate, said receptacle having an elongated opening, and an actuating member for said shifting member extending through said opening.

3. In a device of the class described, article supporting means including an article supporting plate, a movable shifting member for said plate, and means on the exterior of the device to directly lock said shifting member against movement to prevent movement of the supporting means and unauthorized removal of an article.

4. In a device of the class described, a receptacle having a cover fastened against opening and having an open bottom, article supporting means including an article supporting plate within the receptacle, a movable shifting member for said plate and means on the exterior of the device to directly lock said shifting member to the receptacle against movement to prevent movement of the supporting means and unauthorized removal of an article.

5. In a device of the class described, article supporting means including an upwardly movable article supporting plate, support means for the plate, means closing said receptacle to prevent removal of an article at the top of the receptacle, and a shifting member for said plate engaging the plate from below.

6. In a device of the class described, a plurality of movable article supporting plates, and a slidably wedge member to operate said plates for the reception of an article.

7. In a device of the class described, article supporting means including a movable article supporting plate, a slide member to actuate said plate, a pin member projecting from said slide, a fastening member connected to said pin, the device having an 125

elongated slot into and beyond which a pin extends, and means to lock said fastening member to the receptacle on the exterior of the receptacle and consequently lock the slide.

8. In a device of the class described, a plurality of movable article supporting plates, rests for said plates, guide strips, a slide member movable between said guide strips 10 to operate said plates, a wall, a member projecting through said wall connected to said slide, said wall provided with a slot in which said member moves, a hasp on said member, a staple to be engaged by said hasp, in combination with means to lock said hasp to the staple.

9. In a device of the class described, a movable article supporting plate means, a slide member to actuate the same, a frame, 20 a yieldingly mounted plunger device within said frame for the purpose specified, operable through movement of said slide.

10. In a device of the class described, article supporting means including a movable article supporting plate, a slide member to 25 actuate the same, a frame, a yieldingly mounted plunger device within said frame for the purpose specified operable through movement of said slide, and a pivoted plate interior of said frame.

30 11. In a device of the class described, article supporting means including an article supporting plate, a slide member to actuate the same, a frame, a plate pivoted interior thereof, a plunger movable against said plate, a spring device on which said plunger is yieldingly mounted, said spring device having a portion arranged in the path of movement of said slide member.
